UNITED STATES PATENT OFFICE.

ARTHUR A. MITCHELL, OF COLERAINE, MINNESOTA.

EXCAVATING APPARATUS.

1,274,069.

Specification of Letters Patent. Patented July 30, 1918.

Application filed February 20, 1918. Serial No. 218,190.

To all whom it may concern:

Be it known that I, ARTHUR A. MITCHELL, a citizen of the United States, residing at Coleraine, in the county of Itasca and State 5 of Minnesota, have invented certain new and useful Improvements in Excavating Apparatus, of which the following is a specification, reference being had to the accompanying drawings.

10 This invention relates to certain improvements in excavating apparatus and has relation more particularly to a device of this general character especially designed and adapted for use in the digging of ditches or the like 15 and it is an object of the invention to provide a novel and improved apparatus of this general character including an elevated trackway with which an earth working element is engaged together with means associated with said element for effecting an excavating operation.

It is also an object of the invention to provide a novel and improved apparatus of this general character including a digging 25 shovel or scraper having means associated therewith for causing the same to properly engage the ground together with means for maintaining said shovel or scraper in elevated position after the same has been filled. 30 Another object of the invention is to provide a novel and improved apparatus of this general character including a digging shovel or scraper adapted to be elevated as the same is withdrawn over the work and 35 wherein the means for drawing said shovel or scraper serves to elevate the same to permit the desired deposit or dumping of the load received by the shovel or scraper.

An additional object of the invention is to 40 provide a novel and improved apparatus of this general character including a mast adapted to be vertically disposed together with means whereby said mast may be effectively maintained in its vertical position.

45 A still further object of the invention is to provide a novel and improved apparatus of this general character including an up-standing mast which serves as a support for an end of an elevated trackway together 50 with a digging shovel or scraper supported by said trackway, and wherein a pulling cable is connected with the shovel or scraper and which coacts with a boom carried by the mast so that said cable serves to elevate the shovel or scraper when within a 55 predetermined distance of the mast.

The invention consists in the details of construction and in the combination and arrangement of the several parts of my improved excavating apparatus whereby certain important advantages are attained and the device rendered simpler, less expensive and otherwise more convenient and advantageous for use, as will be hereinafter more fully set forth.

60 The novel features of my invention will hereinafter be definitely claimed.

In order that my invention may be the better understood, I will now proceed to describe the same with reference to the accompanying drawings, wherein:

Figure 1 is a view in side elevation of an excavating apparatus constructed in accordance with an embodiment of my invention;

Fig. 2 is a view partly in top plan and 75 partly in section of the apparatus as herein disclosed;

Fig. 3 is a view in front elevation of the apparatus as herein embodied with certain 80 of the parts in section;

Fig. 4 is a fragmentary view partly in elevation and partly in section taken through the shovel or scraper as herein included;

Fig. 5 is a view partly in elevation and partly in section illustrating the hanger 85 traveling upon the cable together with its concomitant parts; and

Fig. 6 is a view in end elevation of the structure as shown in Fig. 5 with the supporting cable in section.

As disclosed in the accompanying drawings 1, 1 denote ground sills arranged in parallelism and which are maintained in predetermined spaced relation through the medium of the cross members 2. Rotatably 95 supported by the forward end portions of the sills 1 is a transversely disposed member 3 which has secured thereto the lower end portions of the members 4 comprised in the mast M. The members 4 extend away from 100 the member 3 in convergence with their outer end portions in contact and mounted upon the contacting end portions of said members 4 is the cap 5 of any ordinary or preferred construction. The members 4 are 105 also tied or connected at predetermined points longitudinally thereof by the transversely disposed beams 6. Secured to the beam 6 at a point midway between the members 4 is a beam 7 extending longitudinally 110 of the mast and said beam 7 adjacent its lower end is provided with a pair of out-

standing and longitudinally spaced eye members 8 through which the removable pin 9 is disposed.

B denotes a boom provided at its inner 5 end with a loop member 10 or the like which is adapted to be disposed between the eye members 8 and through which the pin 9 is also directed. By this arrangement it will be self-evident that the boom B will 10 be held by the mast M for swinging movement.

Secured to the upper end portion of the mast M is a forwardly directed clevis 11 and interposed between said clevis 11 and the 15 upstanding clevis 12 carried by the outer end portion of the member 3 is a flexible supporting member or cable 14. Interposed between the upper portion of the mast M and the rear transverse member 3 is a rigid 20 member 15. The upper end portions of each of the members 4 with the mast M has secured thereto a flexible bracing member 16 which is secured at its opposite or lower end to the rear end portion of a sill 1. It 25 is preferred that the supporting member comprises a plurality of sections connected by a tensioning device 17 for a purpose which is believed to be clearly apparent to those skilled in the art to which my present 30 invention appertains.

To further maintain the mast M in its vertical position, I find it of advantage to employ the guy lines 18. The outer ends of the lines 18 are secured to any suitable anchor 35 and said lines are disposed over the pulleys 19 carried by the cap 5 and downwardly to the winding drums 20 carried by the sills 1. It will be self-evident that by imparting 40 the requisite rotation to the pulleys 19 the desired tension may be imposed upon the lines 18 as the occasions of practice may require.

C denotes a supporting cable or trackway having one end suitably secured to the upper end portion of the mast M and to the 45 clevis 11 if preferred. The cable C is disposed in a direction longitudinally of the ditch or the like and has its outer end portion connected with a suitable anchor. By this arrangement it will be at once self-evident that the cable C will be disposed upwardly in a direction toward the mast M on a predetermined incline. Adapted to 50 travel upon the cable C is a hanger 21 from which depends the frame or shell 22 for the pulley 23. Secured to the lower portion of the frame or shell 22 is a cable 24 which is disposed around the pulley 25 mounted upon a digging shovel or scraper D. The cable 24 is then returned and disposed around 55 the pulley 23 and leads from such pulley 23 a distance sufficient to permit the same to be readily grasped by a workman standing upon the surface of the ground or within the excavation. The pulley 23 is provided 60 with a suitable locking means for holding

the cable 24 against retrograde movement. I do not wish to limit myself in any way as to the character of locking means employed although in the present embodiment of the invention I provide the periphery of the 70 pulley 23 with the eccentric groove 27 whereby the cable 24 when seated within said eccentric groove is effectively clamped against the shell or frame 22 and thereby held against movement over the pulley 23. The 75 shovel or scraper D as herein disclosed has its rear portion bridged by the plate 28 and the rear end of the shovel or scraper proper and the plate 28 has coacting therewith the hinged bottom 29 normally maintained in 80 closed position by any desired latch mechanism 30. It is to be noted that the pulley 25 is secured directly to the plate 28.

Pivotaly engaged with the side walls of the shovel or scraper D is a bail 31. The 85 connections between the bail 31 and the shovel or scraper D are substantially at the forward end of the plate 28. The forward portion of the bail 31 has suitably fixed thereto a clevis 32 and attached to said 90 clevis 32 is the flexible member or cable 33. The cable 33 is directed over a pulley 34 depending from the outer end portion of the boom B and is then operatively engaged with a drum 35 rotatably supported by the 95 sills 1. The drum 35 may be driven by the motor N preferably of an internal combustion type or if preferred draft animals may be hitched directly to the flexible member 100 or cable 33.

Extending rearwardly from the shovel or scraper D are the handles 36 so that as the shovel or scraper D is drawn over the ground the same may be properly controlled by a workman. In order to regulate 105 the depth of penetration of the entering edge of the shovel or scraper D I find it of advantage to secure to the forward end portion of the shovel the flexible member 37 adapted to be adjustably connected with the 110 bail 31.

When the shovel or scraper D is being drawn over the ground to be loaded the cable 24 is unlocked relative to the pulley 23 whereby the shovel or scraper D may readily have the necessary engagement with the ground. When the shovel or scraper D has been properly loaded it is only necessary for the workman to manipulate the cable 24 in such a manner as to lock the same at the 120 pulley 23. The continued pull upon the cable 33 will result in the shovel or scraper D being elevated on account of the upward incline of the supporting cable or track C and the raising of said shovel or scraper to 125 substantially the outer end of the boom B. When in its raised position the shovel or scraper will assume substantially a vertical position and when the swinging bottom 29 is released the contents of the shovel or 130

scraper D may be readily emptied or discharged. It will also be self-evident that by laterally swinging the boom B the desired point of discharge for the shovel or scraper 5 D may be obtained. When it is desired to perform an excavating operation in substantially close proximity to the mast M, I find it of advantage to employ the flexible member or cable 38 of desired length and 10 which is secured at one end to the member 3 and provided at its opposite end with a pulley 39 under which passes the flexible member or cable 33. With the use of this cable 38 and pulley 39 it will be at once 15 self-evident that the shovel or scraper D may be caused to properly penetrate the ground close up to the sills 1 or the mast M carried thereby.

I find it of advantage to employ in connection with the drum 35 a suitable brake 20 40 herein disclosed as of a band type.

From the foregoing description, it is thought to be obvious that an excavating apparatus constructed in accordance with my 25 invention is particularly well adapted for use by reason of the convenience and facility with which it may be assembled and operated and it will also be obvious that my invention is susceptible of some change and 30 modification without departing from the principles and spirit thereof and for this reason I do not wish to be understood as limiting myself to the precise arrangement and formation of the several parts herein 35 shown in carrying out my invention in practice except as hereinafter claimed.

I claim:

1. An excavating apparatus comprising, in combination, an upstanding mast, a boom 40 carried thereby, a track inclined upwardly toward the mast and secured to the upper portion of the mast, a hanger traveling upon said track, a digging implement adjustably engaged with said hanger, and a flexible pulling element secured to the digging implement and engaged with the outer portion of the boom.

2. An excavating apparatus comprising, in combination, an upstanding mast, a boom 50 carried thereby, an elevated trackway secured to the mast, a digging implement,

means coacting with the implement and trackway whereby said implement may be moved along the trackway, and a flexible pulling element secured to the digging implement 55 and engaged with the boom.

3. An excavating apparatus comprising an upstanding mast, a boom carried thereby, a track-way inclined upwardly toward the mast and secured to the upper portion of 60 the mast, a digging implement, means coacting with the implement and the track-way whereby said implement may be moved along the track-way, and a flexible pulling element secured to the digging implement 65 and engaged with the outer portion of the boom.

4. An excavating apparatus comprising an upstanding mast, a boom carried thereby, a track-way inclined upwardly toward the 70 mast and secured to the upper portion of the mast, a digging implement, means coacting with the implement and the track-way whereby said implement may be moved along the track-way, a flexible pulling element 75 secured to the digging implement and engaged with the outer portion of the boom, and a guiding member coacting with the flexible pulling element at a point below the boom.

5. An excavating apparatus comprising an upstanding mast, a boom carried thereby, a track-way inclined upwardly toward the mast and secured to the upper portion of the mast, a digging implement, means coacting with the implement and the track-way whereby said implement may be moved along the track-way, a flexible pulling element secured to the digging implement and engaged with the outer portion of the boom, 90 a flexible member secured to the lower portion of the mast, and a pulley carried by the outer end portion of said last named member and with which the flexible pulling element is engaged.

In testimony whereof I hereunto affix my signature in the presence of two witnesses.

ARTHUR A. MITCHELL.
